UNITED STATES PATENT OFFICE.

EUGEN STAHL, OF DUSSELDORF, GERMANY.

FOOTBALL BOOT AND THE LIKE.

Application filed April 18, 1927, Serial No. 184,553, and in Germany May 5, 1926.

This invention refers broadly to football boots and the like, and it is more particularly concerned with a special construction of the cap of a boot or shoe of the kind referred to, by means of which injury to the players is avoided and the force of the kick may be considerably increased. In view of these and other important objects which will appear from the specification and from the drawing the invention provides a wrapping or covering piece of rubber or the like at the tip of the boot or shoe which is adapted to replace the usual leather cap, or may be employed as a cover for such cap. By means of this construction of the foot ball boot or the like the companion players are protected from injuries during the play, and on the other hand the playing operation is itself facilitated and the technique and the elegance of the game are improved by increasing the force of the kicks or blows of the players and by facilitating the playing around of the opponents by rotatable balls and the like. As an additional advantage of the new construction the life of the boot or shoe is increased, though the leather cap may be made thinner than heretofore or may be entirely dispensed with.

The invention is shown by way of example on the accompanying drawing as applied to an ordinary football boot in Figure 1 in elevation and partial longitudinal section, and in Figure 2 in plan view.

Upon the leather cap 1 of the boot or shoe 2 or as a substitute for such cap a covering cap 3 of rubber or the like is applied which is rigidly connected to the boot or shoe by sewing, pasting for instance or by any other suitable means. The material of the covering piece 3 is preferably particularly reinforced at the toe end of the sole and also at the tread portion. As shown, the reinforcing cap is provided with a bottom or sole portion, a front wall, a top wall, and side walls. The front wall is substantially of the same thickness throughout and presents a contact surface, all portions of which are flush, to secure a full elastic contact surface to stand the shock of contact

with the wall and to enable punts as well as strong kicks to be made without capsing the ball to "English" or curve out of an intended line of trajectory. It will be observed that the bottom wall or sole portion of the reinforcing cap is gradually attenuated toward its rear edge and merges at a gradual angle of inclination into the plane of the bottom of the shoe to which it is attached. By this means the formation of a shoulder liable to trip and cause the player to fall is prevented and a generally rounded surface is provided which forms an elastic surface on which the player may pivot with great facility. It will further be observed that the sides of the reinforcing cap taper toward their rear edges so as to generally follow the contour of the sides of the shoe. This prevents the presentation of any projections at the sides liable to cause the player to trip and adapts the cap to form with the sides of the shoe continuous surfaces which permits the player to properly "dribble" the ball without false strokes.

In practice modifications and alterations of the specific construction shown by way of illustration may be made, and any suitable materials and shapes may be used without departing from the spirit of the invention, as defined in the claim.

I claim:

A football shoe having a reinforcing toe cap applied thereto and comprising bottom, front, top and side walls of resilient material, the front and bottom walls being of greater thickness than the other walls and said front wall being substantially of equal thickness throughout and presenting a vertically continuous contact surface merging on curved lines into the bottom, top and side walls, the bottom wall having its bottom surface sloping toward the sole of the shoe and the top and side walls tapering rearwardly with their outer surfaces sloping so as to lie at their rear edges substantially in line with the sides of the shoe upper.

In testimony whereof I affix my signature.
EUGEN STAHL.
